UNITED STATES PATENT AND TRADEMARK OFFICE
CERTIFICATE OF CORRECTION

PATENT NO. : Des. 540,113 S
APPLICATION NO. : 29/216770
DATED : April 10, 2007
INVENTOR(S) : Ellis G. Short et al.

Page 1 of 1

It is certified that error appears in the above-identified patent and that said Letters Patent is hereby corrected as shown below:

Title Page, Item (75) Inventors:

Third Inventor's surname "Castro", should read -- Casto --.

Signed and Sealed this

Twenty-seventh Day of November, 2007

A handwritten signature in black ink, appearing to read "Jon W. Dudas". The signature is written in a cursive style with a large, stylized "J" and "W".

JON W. DUDAS
Director of the United States Patent and Trademark Office
